UNITED STATES PATENT OFFICE.

GUSTAF LIBERT REENSTIerna, OF BOSTON, MASSACHUSETTS.

DESIGN FOR A PAPER-WEIGHT.

SPECIFICATION forming part of Design No. 22,002, dated November 22, 1892.

Application filed May 31, 1892. Serial No. 435,087. Term of patent 3½ years.

To all whom it may concern:

Be it known that I, GUSTAF LIBERT REENSTIerna, a citizen of the United States, and a resident of Boston, in the county of Suffolk and State of Massachusetts, have invented and produced a new and original Design for Paper-Weights, &c., of which the following, taken in connection with the accompanying drawing, is a specification.

15 This design has for its object to provide a novel, ornamental, and handsome paper-weight.

The leading feature of the design resides in a hemispherical base provided on its surface with a map and surmounted by the representation of an egg.

The design is illustrated by the accompanying drawing, in which the figure is a perspective view of the paper-weight.

20 In the drawing the letter A indicates a base,

which is hemispherical and is provided on its surface with a map of the world or a portion thereof, and the letter B indicates the representation of an egg, which has the appearance of having the small end or point partially 25 broken where it joins the hemispherical base.

The design provides an ornamental paper-weight, which presents a distinguishing and characteristic appearance to the eye.

What I claim is—

30 The design for a paper-weight, substantially as shown and described.

In testimony whereof I have signed my name to this specification, in the presence of two subscribing witnesses, on this 23d day of 35 May, A. D. 1892.

GUSTAF LIBERT REENSTIerna.
